UNITED STATES PATENT OFFICE.

CONSTANTINE SAVITSKY, OF DENVER, COLORADO.

LAMP ATTACHMENT.

1,316,980.

Specification of Letters Patent. Patented Sept. 23, 1919.

Application filed November 29, 1918. Serial No. 264,500.

To all whom it may concern:

Be it known that I, CONSTANTINE SAVITSKY, (formerly a citizen of Russia, having declared his intention to become a citizen of the United States), residing at 1218 Quitman street, in the city and county of Denver and State of Colorado, have invented certain new and useful Improvements in Lamp Attachments; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to attachments for lamps and is to be used in connection with a cooking attachment. The object is to reinforce the shade support whereby heavier cooking vessels may be safely placed on the cooking attachment.

Briefly stated, the invention comprises two flanged and channeled members to be bolted together about the bead extending around the side of the lamp, the upper one of these members supporting a plurality of hinged arms shaped at their upper ends to receive the lower edge of the lamp shade.

In the drawings:

Figure 1 is an elevation showing the application of the improvement.

Fig. 2 is a plan of the attachment.

Fig. 3 is a vertical section indicated by the line 3—3 of Fig. 2 and showing also the application to a lamp.

Fig. 4 is a similar view indicated by line 4—4 of Fig. 2.

Fig. 5 is a similar showing indicated by line 5—5 of Fig. 2.

Fig. 6 is a vertical section showing the cooking attachment in detail; and

Fig. 7 is a horizontal section on the line 7—7 of Fig. 6.

In Fig. 1 an ordinary metal lamp with chimney, shade and adjustable shade supports is shown, the supporting arms A of a cooking attachment B resting upon the upper edge of the shade, and a cooking vessel C being mounted on the cooking attachment B.

The invention is the reinforcing or auxiliary attachment comprising the upper annular ring, 12, and the lower annular ring,

13. These rings are shaped to fit the bead D of the lamp as shown, and have horizontal flanges 14 and 15 respectively which are bolted together by bolts 16 and thus secured to the lamp. The lower ring has a depending bracing flange 113 which lies against the body of the lamp.

At each of several properly spaced points, a pair of ears 17 is formed on the upper ring 12. These ears receive a pintle 18 which passes through an eye 19 formed in the lower end of the standard 20, thereby forming a hinge joint. The upper end of each standard is cupped as shown at 21 to form a firm support for the shade. The hinge joint permits the supports 20 to be adjusted along with the original shade holders to take different size shades.

It will be seen that this improvement adds greatly to the value of the entire device as a cooking means. The ordinary shade supports are never strong enough to support a cooking attachment and a vessel of any appreciable size. But with my present attachment, a total weight of about twenty pounds may be supported on the cooker. This makes a very efficient compact cooking or water-heating arrangement for small quarters.

As above stated, the cooking attachment is supported upon the lamp shade S by supporting arms A. Upon each pair of adjacent arms A a semi-circular band 30 is mounted. These bands have slots 31 in which headed rivets, 32, secured to the arms A are slidable. Centrally positioned on each band is a knob 33. By this construction when the knobs 33 are grasped and pulled apart all of the arms A are separated and the shade-engaging portions 34 freed from the upper edge of the shade as the attachment is being positioned or removed.

The arms A support the cooking attachment B. The latter is composed of the tray 35, to which the arms A are riveted, the tray being provided preferably with handles 36. Fitted snugly to the tray 35 is a sleeve 37 having an annular flange on its lower end said flange underlying the tray 35. Within the sleeve 37 there is a cylinder 40, whose upper end is flanged at 41 to rest upon the top of the lamp chimney or flue F, while the cylinder is spaced from the flue slightly. The lower end of cylinder 40 is flanged at 42 and supports

an annular member 43 upon which the flange on the lower end of sleeve 37 rests. By this arrangement the weight of the attachment is supported both by the lamp shade S and the chimney or flue F.

Located in the tray 35 is a pan 45 whose inner edge is turned up as shown. An outer sleeve 46 fits about the sleeve 37 and has a lower flared portion 47 which snugly fits 10 over the upturned inner edge of the pan 45, or is otherwise tightly connected with the pan. The object of this construction is to collect liquid which may boil over from the cooking vessel C.

15 A supporting platform 50 is mounted in the pan and is provided with an inwardly extending rim 51, which engages the sleeve 46 and centers the platform. The member 50 also has an inturned reinforcing flange 20 52 and in this and the rim 51 the standards 53 are mounted by means of nuts and threads as shown. Upon these standards a supporting tray 55 for cooking vessel C is mounted, the tray having an upturned 25 inner rim 56 and being provided with apertures 57 near its outer edge. If the vessel is smaller than the tray it rests upon rim 56; if it boils over the liquid will flow through apertures 57 and fall into the pan 30 45. If the vessel is larger than the tray 55, liquid boiling over will fall directly into the pan. The rim 60 properly spreads the heat.

I claim:

35 1. In combination with a lamp having a shade and a cooking attachment supported upon said shade, the body of said lamp having an annular bead at its outermost portions, of an annular member mounted upon 40 said lamp body about said bead, and a plu-

rality of shade-supporting arms extending upwardly from said annular member.

2. In combination with a lamp having a shade, the usual adjustable shade holders, and a cooking attachment supported upon 45 said shade, the outermost portions of the body of the lamp having an annular bead, of an annular member mounted upon said lamp body about said bead, and a plurality of hinged shade supporting arms extending 50 upward from said annular member.

3. An auxiliary shade-supporting attachment for lamps, having beaded bodies and equipped with cooking devices mounted upon the shades, comprising a pair of an- 55 nular channeled members adapted to be secured together to inclose the bead and be supported thereby, and a plurality of shade supporting arms extending upward from said members.

4. In combination, a lamp having a shade and a flue, supporting arms resting upon said shade, a heating attachment mounted upon said arms, a sleeve about said flue having means thereon to engage the top of 65 the flue, and means also on said sleeve to engage and support said heating attachment, whereby said attachment is supported both by the shade and the flue of the lamp.

5. In combination, a lamp having a shade 70 and a flue and means to support said shade, auxiliary means mounted upon the outer portion of the body of the lamp to support the shade, and a cooking attachment mounted upon said shade and having means to engage the top of the flue to assist in supporting said attachment.

In testimony whereof I affix my signature.

CONSTANTINE SAVITSKY.
